BATTERY PASTING MACHINE

Alvy C. Yerkey, Maywood, Ill.

Application November 1, 1937, Serial No. 172,315

2 Claims. (Cl. 226—39)

This invention relates to a battery pasting machine.

An object of the invention is to provide a battery pasting machine equipped with improved means for removing excess paste from the grids. A further object is to provide a grid pasting machine having a hinged hopper which can be readily turned to one side to permit direct access to the belt means below the hopper. Other specific objects and advantages will appear as the specification proceeds.

The invention is illustrated in a preferred embodiment, by the accompanying drawings, in which—

15 Figure 1 is a vertical sectional view, the section being taken as indicated at line 1 of Fig. 2; Fig. 2, a plan sectional view, the section being taken as indicated at line 2 of Fig. 1; and Fig. 3, a longitudinal sectional view, the section being taken 20 as indicated at line 3 of Fig. 2.

In the illustration given, A designates a frame supporting a belt bed A'; B, a hopper; and C, grid scraping mechanism.

The frame A may be of any suitable construction. In the illustration given, a metal frame work 10 is shown equipped at its top with laterally turned flanges 11 upon which is supported the bed A'. In view of the fact that the invention does not reside directly in the frame, a detail description is believed unnecessary. Upon the bed A' travels a belt 12 which is driven by suitably journaled rollers (not shown), the rollers in turn being driven by a motor (not shown). As illustrated, the belt travels beneath a hopper B and carries grids below the hopper and beyond the hopper.

The hopper B may be of any suitable construction. In the illustration given, the hopper is provided with an upper funnel-shaped portion 13 and a lower base portion 14. The base portion 14 is equipped on each side with lateral extensions 15 and 16. The extensions 15 are apertured to receive a hinged bolt 17 which passes through the extensions 15 and also through the supporting lugs 18. By this means, the hopper is effectively hinged on the one side.

The extensions 16 carry a flange 19 which is adapted to be releasably secured to the flange 11 by means of bolts 20.

50 The scraper mechanism C will now be described. In the illustration given, the rear base portion 14 of the hopper B is provided near its upper end with an angle iron support 21 through which passes bolts 22, the lower ends of which enter a scraper guide member 23. Springs 24 are carried

by pins 22 and engage the guide 23 so as to urge it downwardly. The guide 23 is releasably secured to the hopper 14 by means of bolts 25, the openings within the guide 23 being sufficiently wide to permit adjustment of the guide. The 5 lower portion of guide 23 is provided with an inwardly extending portion 26 which is snugly received within the U-shaped scraper 27. The guide member 23 is urged inwardly by spring 28 which is housed between the screw 29 extending into the guide 23 and bolt 30 which extends through the plate 31, a lock nut 32 being provided between the head of bolt 30 and plate 31.

The scraper member 27 is thus slidably supported between the wall 14 and the scraper guide 15 23 for lateral movement. At one end, the member 27 is cut away to receive a link arm 33 which is secured to the member 27 by the pivot 34. The link 33 at its other end is connected to a rotatable head 35 by means of an eccentric pin 36. 20 The head 35 is driven by shaft 37 which is equipped with a bevel gear 38 meshing with the bevel gear 39 carried by shaft 40. The shaft 40 is driven by a source of power not shown. The rotation of shaft 40 turns by means of the meshing gears 38 and 39, shaft 37 and head 35. The eccentric pin upon head 35 rapidly reciprocates the scraper slide 27.

In operation, a grid is fed on the receiving side of the machine below feed roller 41 and is 30 carried by belt 12 along the underside of hopper B. As it passes through hopper B, the paste settles into the grid and packing rollers or paddles may be provided (not shown) for further forcing the paste into the grid 42. The grid, as it emerges 35 at the opposite side of the hopper, passes under this reciprocating slide 27 which is urged downwardly by spring 24 and inwardly by spring 26. The reciprocating slide causes the paste to be pressed against the little fins of the grid on 40 opposite sides of each opening, thus producing a thorough packing of the paste within the grid and preventing the paste from being pulled out. The grid is then carried forward by the belt 12 for succeeding operations.

45 It will be observed that the scraper plate 27 may rise against the force of spring 24 to prevent injury to the mechanism in case two plates are drawn under the plate or in case of any other obstruction. If access to the bottom of the hopper is required, this may be readily obtained by unscrewing bolts 20 and then lifting the flanges 16 so as to allow the hopper to turn upon its pivot shaft 17, thus causing the hopper to swing to one side of the apparatus. As soon as the 55

belt is cleared and the mechanism repaired, if this should be necessary, the hopper can be swung back to its former position and readily bolted in place.

- 5 The reciprocating scraper mechanism, operating as it does in a lateral direction, prevents the paste from being stripped out of the grid, as is the case with the usual scraper device, and, instead, packs the paste firmly within the grid by 10 scraping the paste laterally, first on one side and then on the other, this lateral scraping against the individual fins of the grid tending to lock it firmly within the grid. It will be observed that the battery grid 42 is provided with 15 longitudinal extending fins which run at right angles to the reciprocating scraper and cooperate with the scraper in the packing of the paste within the grid.

The apparatus is extremely simple in construction and operation while performing an entirely new function, namely of packing the paste within the grids by lateral movement of the scraper, the scraper moving first in one direction and then in the other direction at right angles to the fins 25 of the grid.

While in the foregoing specification, I have set out one example by way of illustration, it will be understood that many changes can be made in

the details of construction without departing from the spirit of my invention. The foregoing description has been given for clearness of understanding only, and no unnecessary limitations should be understood therefrom, but the appended claims should be construed as broadly as permissible, in view of the prior art. 5

I claim:

1. In a grid pasting machine of the character set forth, a conveyor belt, means for driving said belt, a hopper supported over said belt and equipped on one side with a hinge whereby said hopper may be moved to a position on one side of said belt, a scraper plate guide carried by said hopper, a scraper plate slidably secured between 15 said guide and said plate, and means for reciprocating said scraper plate laterally.

2. In a grid pasting machine of the character set forth, a conveyor belt, means for driving said belt, a hopper supported over said belt and 20 equipped on one side with a hinge whereby said hopper may be moved to a position on one side of said belt, a scraper paste guide carried by said hopper, a scraper plate having longitudinal interlocking connections with said guide whereby 25 said scraper plate may reciprocate laterally, and means for reciprocating said scraper plate.

ALVY C. YERKEY.
